UNITED STATES PATENT OFFICE.

CHARLES Y. TURNER, OF NEW YORK, N. Y.

DESIGN FOR A FLAG.

40,336.

Specification for Design.

Patented Nov. 9, 1909.

Application filed June 28, 1909. Serial No. 504,941. Term of patent 14 years.

To all whom it may concern:

Be it known that I, CHARLES Y. TURNER, a citizen of the United States, residing at New York, in the county of New York and State of New York, have invented a new, original, and ornamental Design for a Flag, of which the following is a specification, reference being had to the accompanying drawing, forming part thereof.

The figure is a plan view of a flag showing my new design.

The flag is a tricolor, consisting of three

(3) equal horizontal stripes, of Nassau orange, white and light blue. In the center of the middle stripe, are the initials H. F. in red. On each side of the initials is a branch of laurel in natural color.

I claim—

The ornamental design for a flag as shown and described.

CHARLES Y. TURNER.
